(57) **CLAIM**

The ornamental design for a faucet handle, as shown and described.

DESCRIPTION

FIG. 1 is perspective view of a faucet handle incorporating our new design, viewed from in front of, above, and from the left side of the faucet;

FIG. 2 is a front elevation view thereof;

FIG. 3 is a rear elevation view thereof;

FIG. 4 is a top plan view thereof;

FIG. 5 is a bottom plan view thereof;

FIG. 6 is a left-side elevation view thereof, with the right side being a mirror image of the left side; and,

FIG. 7 is a perspective view showing the faucet handle of FIGS. 1-6 in combination with the remainder of a faucet in which the handle is usable.

The broken lines in FIGS. 5 and 7 are for illustrative purposes only and form no part of the claimed design.
